UNITED STATES PATENT OFFICE

ARTHUR H. ADAMS, OF LA GRANGE, ILLINOIS

TRAIN-CONTROL SYSTEM

Application filed April 22, 1926. Serial No. 103,720.

This invention relates to train control systems, and more particularly to that class of systems in which indications governing the progress of a train are continuously received 5 on the train.

It is the object of the invention to provide new and improved means for indicating the speed at which the train should move during certain traffic conditions, e. g., in a "stop" or 10 "occupied" block, and to control the automatic application of the brakes if a predetermined speed is exceeded.

In accordance with the present invention this is accomplished by providing on the train 15 a timing device which operates at a predetermined rate of speed. Means, preferably in the form of a recorder, are provided for comparing the speed of the train with that of the timing device and for preventing the automatic application of brakes as long as the 20 train proceeds within the predetermined speed limit. As soon as this speed is exceeded, the recorder is operated to permit the automatic application of the brakes.

25 In accordance with one of the features of the invention the recorder consists of counting relays which are operated in one sense by an interrupter mounted on the axle of the locomotive, and in the opposite sense by the timing device. Means are provided for visually indicating to the engineer that he exceeds 20 the allowed speed. The engineer is thus given an opportunity to forestall the automatic application of the brakes.

35 The invention is illustrated in connection with an inductive receiver of a continuous influence system, described and claimed in my copending application Serial No. 610,804, filed January 5, 1928, but it will be obvious to 40 those skilled in the art that it is capable of various other applications without departing from the spirit thereof.

In the drawings, Fig. 1 represents a block or section of track insulated from adjacent 45 blocks with a diagrammatic showing of a controller for producing codes of impulses in the track and with a diagrammatic representation of a locomotive in the block; Fig. 2 represents one type of current wave form that 50 may be produced in the track and the cor-

responding voltage wave form induced in the receiver; Fig. 3 represents another form of track wave and the corresponding voltage wave form in the receiver; Figs. 4-9 are schematic representations of various codes that 55 may be used; Fig. 10 is a schematic illustration of as much of a simple form of receiving apparatus and receiving circuit on the locomotive as is necessary for a clear understanding of the invention by one skilled in the art; 60 and Fig. 11 is a schematic illustration of one form of the track code controller symbolized or diagrammatically shown at 3 and 6 of Fig. 1.

In Fig. 1, 1 are rails bonded to form each 65 a continuous conductor from end to end. 2 are insulators electrically separating the rails of the one block from adjacent blocks. 3 is a circuit connection between the two rails at the entering end of the block and will usually 70 comprise a relay or relays for signaling and other purposes. 4, as indicated, is a symbol for a locomotive carrying, ahead of the front wheels, inductors 5, more clearly shown in Fig. 10 in their relation to the rails 1. 6, as 75 indicated, is a track current controller. Its function is the setting up of suitable codes of impulses in the rails of a block as determined by the condition of the track ahead. As is well known, such controllers comprise a 80 source of electrical current, either in the form of a generator or battery, or in the form of power lines from a distant source of current supply, and an interrupter, switch, pole-changer, reversing device, rheostat or the like, 85 for making, breaking, reversing or otherwise varying the current flowing in a given circuit. Reasonably reliable speed-controlling or time-measuring means is also comprised in any such controller. The controller 6 need 90 not even be situated near the track, but the conductors connecting it thereto may be extended so that one controller may serve a number of sections of track. The connection 95 between the controller and the track circuit may be inductive, as through a transformer, instead of conductive as illustrated. In fact, any well-known means may be used to produce a current flow in the track of the character described. Merely to fix the ideas, a 100

suitable controller and a cooperative track relay are shown in Fig. 11 and will be described below.

The upper line of Fig. 2 is a graph or current-change curve in which the horizontal dimensions represent time and the vertical dimensions above the line 0—0 represent positive current, and the vertical dimensions below the line 0—0 represent negative current. The lower line of Fig. 2 shows the corresponding voltage for the receiver and the two, together, illustrate how a gradual increase of current in the track induces a very small, steady voltage in the receiver, and how the abrupt dying out of the current in the track induces in the receiver a relatively high but brief voltage wave corresponding in sign to the original track current.

Fig. 3 is a graph substantially identical with that of Fig. 2, also showing track and receiver curves and illustrating how abrupt reversals of current direction in the track induce in the receiver relatively strong but brief impulses corresponding in sign to the track impulse.

Fig. 4 symbolizes a preferred code of track impulses (or we may read them as detected in the receiver) which will permit a locomotive carrying the receiver of Fig. 10 to travel at any speed at which the engineer may desire to run without automatic interference. This code I have termed the "clear" or "unlimited" code. In this figure and in Figs. 5-9 inclusive, horizontal dimensions represent, in a general way, time; the signs + and - above and below the line 0—0 represent each one an impulse of positive or negative polarity and are with equal logic in most cases understood to symbolize either or both the impulses in the track or in the receiver.

In the code of Fig. 4, "clear" code, it will be seen that the time represented by the dimensions A is relatively brief between each impulse and the next effective one. In this case, and because an unbiased polarized relay is utilized, the next effective impulse is the next of the opposite polarity. Without limitation to any definite value for this time and merely to fix the ideas, this period may be of the order of one second. It must be understood that while this code is the only "clear" code illustrated and is the preferred one for reasons of simplicity, any timed sequence of impulses will be satisfactory as a "clear" code in which the intervals between effectively received impulses are never longer than the suitable time A. Thus a regular code of two positive impulses followed by two negatives and repeated indefinitely at, say, two-second intervals, would be the equivalent of the illustrated "clear" code of Fig. 4, assuming the polarized relay to be of the unbiased type. If the polarized relay 23 of the receiving circuit Fig. 10 is biased,

which is readily done by adjusting its armature nearer to one pole than to the other so that said armature has a normal position of rest when no current is flowing through coils 21 and 22 and does not, as I prefer it to do, remain on either side according to its last operation, then the "clear" code may be composed entirely of impulses of one polarity. Such impulses could be of the type of the positive track and receiver impulse forms of Fig. 2. They would have to be repeated at intervals sufficiently brief, i. e., at intervals not exceeding a time A found suitable to properly operate the receiving circuit.

Fig. 5 illustrates a code of impulses which, in cooperation with the receiving apparatus and circuit (Fig. 10) carried on the locomotive, will act to prevent the engineer from continuing at a speed higher than a certain predetermined limit when the locomotive is in a block in the rails of which this code is being produced. While the details of the receiving circuit may be modified in many ways, in the disclosed receiving circuit the code of Fig. 5 will automatically apply the brakes under certain conditions within a brief period after this code has begun to act upon the receiver. One of these conditions is that the train be moving faster than a certain speed. Another is that the engineer has not by a manual application of the brakes already started to reduce the speed of his train. The above is merely explanatory of the function of this code of Fig. 5 and the detailed conditions and operation will be more particularly described below. This code and those having the same general speed-limiting function are herein generically termed "caution" codes. It will be observed that the time B in the code of Figs. 5-8 is the longest time between effective impulses. With an unbiased polarized receiving relay, the time between effective impulses is the time from the first impulse of one polarity to the first of the opposite polarity. Time B is several times longer than the time A of the "clear" code. Merely to fix the ideas, we may take time B as of the order of seven seconds. It should be noted that one of the merits of timed impulse codes for controlling train speeds is that the times B may be largely varied according to the speed limit desired by different railroads, in different portions of one railroad, in different blocks behind an occupied block, even if desired, at different times of the day or of the year, or for other reasons as may be dictated by experience.

With a biased polarized receiving relay this code might equally well be composed of nothing but positive impulses, e. g., of the type of Fig. 2, occurring at proper time intervals B. No "clear" or "caution" codes of this type, i. e., composed solely of impulses of one polarity, have been illustrated in the drawings for

the reason that the polarized relay 23, shown in Fig. 10, is not biased, i. e., relay 23 has a balanced adjustment and remains in the position to which it was last operated. Such uniform 5 polar "clear" or "caution" codes would therefore not cooperate with the receiver shown. The possibility of using codes of one polarity is pointed out here merely to emphasize the fact that the intervals of time between effectively received impulses are the most important 10 distinguishing characteristics of these different codes.

Fig. 6 illustrates a "caution" code identical with that of Fig. 5 except that the first positive impulse induced in the receiver is succeeded by a series of positive impulses having no effect whatsoever on the preferred receiver, and the first negative impulse is likewise succeeded by negative impulses without 20 effect. This variation is illustrated to show the flexibility of the system, and, while of no advantage in the practice of this present invention as shown, might be preferable to that of Fig. 5 for use in connection with certain 25 types of track current control or local signaling circuits or with certain types of track relays. Thus if the track current-change curves of Fig. 2 are used, the code of Fig. 5 would involve a relatively long time 30 with no current in the rails 1 and through the connection or track relay 3. If we suppose 3 to be a signaling relay requiring to be held up during the "caution" code, track impulses of the form of Fig. 2, repeated as 35 in the code of Fig. 6, might, with certain types of relays, more readily accomplish this end for the signal engineer. The relationships between the codes in the one block and in the block behind or before and the means 40 of producing these relationships may be greatly varied within the spirit of this invention. The above remarks as to the possible superiority of the code of Fig. 6 under certain circumstances are merely illustrative of 45 the inherent flexibility of the present track current code system.

Fig. 7 illustrates a third "caution" code in which the time B, as before, is the period from the occurrence of the first impulse in 50 the receiver of one polarity until the occurrence of the first of the opposite polarity. It differs from the codes of Figs. 5 and 6 in that a brief period A is interposed between the longer periods B, and is typical 55 of a whole class of possible, but not further illustrated, codes in which periods of "clear" code are regularly interrupted by relatively long "caution" periods or code pauses B.

Fig. 8 illustrates a code identical with that 60 of Fig. 7 except that the polarities are reversed and with the further exception that the times B are filled with repeated impulses of the one polarity after the manner of the code of Fig. 6.

Fig. 9 illustrates three of the many possible

varieties of "stop" block codes and a fourth code or condition of an "occupied" block. In the present disclosure there are provided means whereby low speed running, limited to perhaps 10 or 15 miles an hour, is permitted in an "occupied" block and also in the block, termed a "stop" block, just preceding any "occupied" block. There are, in a "stop" block and in an "occupied" block, as illustrated, different current conditions or codes. But since, 70 in cooperation with the receiver of Fig. 10, they do permit a low speed advance, they are also generically "caution" or speed limiting codes. However, to distinguish from the codes of Figs. 5, 6, 7 and 8, they are herein referred to as "occupied" and "stop" codes. 80 And because the receiver of Fig. 10 does not differentiate between the "stop" and the "occupied" codes, the same low speed limit in this illustration of my invention applying to 85 both, the following description of the operation of the receiver refers to these codes only as "occupied" codes.

The one essential characteristic that the four codes illustrated in Fig. 9 have in common is that, with the exception of a single first impulse in several cases, they produce no effect whatever upon the receiving relay. They are, to all intents and purposes, the same in effect on the receiver of Fig. 10 as long code pauses 90 B of the various types shown in the "caution" codes of Figs. 5-8. The second code shown in Fig. 9 is a series of repeated negative impulses. The third shown is a long continued direct current flow in the track in a positive 95 direction, i. e., an indefinitely extended wave of the type of the track wave of Fig. 3. A continued flow in the negative direction in the track would be another possibility. The fourth code shown in Fig. 9 is merely dead 100 track, i. e., without current of any kind. This is the code or condition in an "occupied" block behind the occupying train or vehicle. Obviously, the third and the fourth are identical 105 as far as the impulses induced in the receiver are concerned, and it will be seen when the receiver circuit of Fig. 10 is described, that all four are identical as far as effects on the polarized receiving relay are concerned.

The advantage of the last two codes will be 110 particularly apparent when it is considered that failures of the source of track energy S of Fig. 1, the failure of the track current controller 6 of Fig. 1, the opening of the track circuit or the short-circuiting thereof, at any 115 point between the locomotive and the controller 6, all act to produce this form of code. Likewise, any failure of the receiving mechanism of Fig. 10 to receive the impulses that may be in the track has the same effect on the 120 train control mechanism as these last two codes. There is a similar advantage in the choice of the first two codes illustrated in Fig. 9, in that any failures in the track current controller affecting one polarity only, 125

or any failures in the receiver of Fig. 10, such that it can receive or amplify one polarity only, result in the equivalent of the first or the second code of Fig. 9. To those acquainted with the train control art, the value of this choice of codes whereby failures produce the effect of a more precautionary signal is obvious.

In Fig. 10, 1 are the rails of Fig. 1 shown in cross-section, 5 the inductors or inductive receivers each comprising an iron core mounted on the locomotive in a position as near to the rail as the necessary clearances of railroad usage will permit. These cores are each surrounded by a winding 7, and these two windings are preferably connected in series, and also in such a manner that the electromotive forces, generated in the windings 7 by changes of current in the rails 1, shall reinforce each other. The relative direction of flux in the two inductors, when the current in the track circuit is in one direction, is indicated by arrows on the dotted lines 8. From the inductors two conductors 9 and 10 lead respectively to the filament and grid of a three-electrode electron tube 12. 11 is a filament heating battery or so-called "A" battery; 13 is the plate circuit battery usually called the "B" battery. The plate circuit is completed by conductors 14 and 15 through the primary 16 of a transformer. 17 is the iron core of this transformer. 18 is the secondary; conductors 19 and 20 complete the secondary circuit through the windings 21 and 22 of a polarized relay 23. As illustrated, this relay is electromagnetically polarized by energy from a battery 24 and a polarizing winding 25, but a permanent magnet may be used in place of an electromagnet as a source of polarizing flux. The windings 21 and 22 are wound and connected in such a manner that a current flow in either direction in the secondary circuit 18, 20, 22, 21, 19 tends to produce opposite polarities at the poles 26 and 27. The polarizing flux due to the winding 25 enters the armature 28 substantially at the center and a portion goes to the right-hand half of the armature returning through pole 26 and the common frame 23 of the relay. A portion of this polarizing flux goes to the left-hand half of the armature through pole 27 and returns through the common frame 23. Thus the flux due to the polarizing coil is in the same direction through both poles 26 and 27. The preferred adjustment of the relay is such that the pull of these two poles is substantially equal when tongue 29 is held half-way between its two positions of contact with conductors 31 and 32.

At this point it may again be mentioned that if the relay were such that tongue 29, when no current flows in coils 21 and 22, always returned to lie on the same side, it would respond only to impulses of one polarity. If we assume that it lies as actually shown in the

drawing, and if we call positive that impulse that will cause it to move to its other position, this makes clear the statement, above, that by biasing the polarized relay of the receiver, a track code of impulses like those of Fig. 2, but of one polarity, will be effective. As will be better understood after the whole operation of this receiving structure has been described, a very refined and exceptionally quick design for the left-hand quick-acting slow-release relay 34 would, in this event, be required. As stated above, the biased polarized relay would be less sensitive. The change offers no sufficient advantages over my preferred structure so far as I can perceive to compensate for these two disadvantages. It is possible again, as stated above, that for certain track circuit purposes a code of one polarity would be a simplification.

Resuming the description of the structure as shown, the flux due to currents in the windings 21 and 22 being of opposite sign in the two poles, opposes the polarizing flux in the one pole and aids it in the other. Due to the well-known law that the pull between a pole and an armature is proportional to the square of the average density of the flux, multiplied by the effective cross-section of the flux, this type of relay can be made responsive to very small impulses by increasing the polarizing flux. It is for this reason that electromagnetic polarizing means are preferred. All of this polarized relay construction is of course well known in the art.

The armature 28 of the polarized relay carries a light tongue 29 which is grounded at 30 and which makes contact in the one position with conductor 31, in the other with conductor 32. This armature is pivoted on a knife edge 33 and, in the absence of current through windings 21 and 22, retains the contact which it last made with some firmness due to the polarizing flux which holds the armature strongly to the nearer one of the poles 26, 27. In the diagram more polarizing flux is temporarily passing through pole 27 than through pole 26 because of the temporarily larger air-gap at pole 26. The tongue 29 is therefore firmly held in contact with conductor 31.

Polarized relay tongue 29, due to received and amplified impulses of alternate polarity, closes the circuit alternately from ground 30 through conductor 31 or 32 and either one of two quick-acting slow-release relays 34 to battery and ground. Relays 34 may be of any suitable construction well known in the art but are very simply and preferably made of the simplest D. C. relay form, with the addition of a heavy copper collar or sleeve 35 which, acting as a short-circuited secondary, renders the action of the relay sluggish, more especially on releasing. By a suitable adjustment and by using a proper amount of

70

75

80

85

90

95

100

105

110

115

120

125

130

energy in the coils of these relays, they can be made much slower in releasing than in attracting their armatures 36.

The armatures 36 of quick-acting slow-release relays 34, when these relays are energized close a series circuit from ground through the two armatures 36 and their two front contacts 37, conductors 38 and 67, the extreme left-hand contacts of relay z and I^c , conductor 39, and in multiple through the left-hand windings of relays 40 and I , to battery and ground. A branching circuit 41 from conductor 67 includes a green signal lamp 42 normally in parallel with the left-hand windings of relays 40 and I .

Relay 40 is shown with two armatures, but this is done for simplicity in the diagram. This relay and those like it in the drawing are preferably of one of the well-known D. C. types having an armature closing, when energized, two or more separate circuits. For brevity I shall hereafter refer to the right and left-hand armatures just as shown in the drawing. Relay 40 has a right-hand winding connected (aiding the left-hand winding) through the right-hand armature when 40 is energized and then through conductor 43 to a wiper 44 which bears on an interrupter 45. Interrupter 45 has a relatively short insulated segment and a grounded conducting segment. It revolves in a clockwise direction as viewed in the drawing and is carried by or operated from a wheel or axle of the locomotive. A second wiper 46 bears on interrupter 45 at substantially 180° distance from wiper 44 and connects ground to certain relay armatures through conductor 47, as will be explained below.

The left-hand armature of relay 40 is grounded and, when relay 40 is energized, closes the circuit to conductor 48 through the right-hand winding of relay 50 to battery and ground. Relay 50 has a left-hand winding of which the circuit is closed from the grounded interrupter 45, through wiper 46, conductor 47, and its own left-hand armature to grounded battery, when relay 50 is energized. This circuit is, of course, open at the interrupter when wiper 46 is on the insulating segment. The right-hand armature of relay 50 is grounded and, when 50 is energized, closes a circuit containing the left-hand winding of relay 60. The relay 60 has a right-hand winding, the circuit of which is closed when it is energized, through its own right-hand armature, conductor 43, wiper 44 and grounded interrupter 45. This circuit is, of course, open at the interrupter when wiper 44 is on the insulating segment. The left-hand armature of relay 60 is grounded and when energized closes a circuit containing the right-hand winding of the next counting relay (not shown), and so on for an indefinite number of relays. The number of these relays to be used, which I have termed the

counting relays of the "caution" speed-limiting string or series, is dependent on the speed limits to be enforced and the length chosen for the code pauses or "caution" intervals B.

For simplicity in the drawings I have shown of this first string or series of counting relays only the first three designated 40, 50, 60, and the last three designated x , y , z . It will be clear from a comparison of the figures on the drawings that the relay x is connected exactly like the relay 50, the relay y is connected exactly like the relay 60, and the last relay z again like relay 50.

Relay x is energized through its right-hand winding by the left-hand armature of the preceding relay and is periodically energized through its left-hand winding by its own left-hand armature and the wiper 46 of interrupter 45. The grounded right-hand armatures of relay x close, when the relay is energized, one additional circuit through conductor 49 and yellow signal light 51, to grounded battery and a further circuit through conductor 49^a and red signal light 51^a, to grounded battery. Relay z is, by conductor 68, connected to the first relay 40^a of a second or continuation series, which I have termed the "time of grace" recording string of relays, just as relay 50 is to 60. Relay 40^a is succeeded by another relay (not shown), and so on to the last relay z^a . For simplicity of the diagram only the first and the last relays 40^a and z^a are shown of this second or "time of grace" series.

A further set of counting relays I, II, III . . . I^a , I^b , I^c , is provided for the purpose of limiting the speed of the train within an occupied or stop block by comparing the speed at which the axle revolves with the speed of a constantly operating timing device provided in the cab. The timing device is diagrammatically illustrated at T. It consists of a constantly rotating interrupter provided with a short grounded segment whereby during each revolution of the device ground is connected for a short period of time to a wiper t . The timing device should be protected against tampering. A grounded interrupter 45^a is mounted on the axle in substantially the same manner as interrupter 45, this interrupter co-operating with wipers 44^a and 46^a to control the associated set of counting relays. The interrupter 45^a is provided with any desired number of interrupter segments so as to deenergize a predetermined number of counting relays during each revolution of the axle. The counting relays I to I^c are placed under the control of the interrupter 45^a at the same time that the relays 40 . . . z are placed under control of interrupter 45, i. e., upon deenergization of either slow release relay 34. The number of interrupting segments of interrupter 45^a and the number of relays in the string I . . . I^c is so chosen that, when both strings 40 . . . z and I . . . I^c are released to the control of their respective inter-

rupters, the latter string will be completely deenergized and relay I^e therefore deenergized in less than half of the time taken to release relay z . This is in order that relay I^e shall always be found deenergized when relay z becomes deenergized in any "caution" code cycle. This will be more fully explained hereinafter.

Relay I^e , by its grounded right-hand armature and conductor 68, holds energized relay 40^a of the "time of grace" series. This control is in multiple with the control by the right-hand armature of relay z . Thus relay 40^a does not release when its right-hand coil is deenergized by the insulating segment of interrupter 45, brush 44 and conductor 43, unless and until both relays z and I^e are released.

The circuit from ground through the armatures 36 and contacts 37 of slow-release relays 34, conductors 67 and 39 to the left-hand windings of both relays 40 and I to grounded battery, passes through two contacts in multiple, these being the contacts of the extreme left-hand armatures of both relays z and I^e .

Timer T, when revolved to the position where wiper t is on the grounded segment, establishes a circuit through conductor 80^a, the extreme right-hand armature of relay I^e and its contact, conductor 79^a and the right-hand winding of relay I to grounded battery. By this circuit, timer T at regular time intervals energizes relay I , which energizes relay II , etc., and thus energizes the whole string. If, however, the last relay, I^e , is released when T is electrically connected with t , the circuit is broken between conductors 80^a and 79^a and then timer T cannot reenergize relay I or any of the string $I \dots I^e$.

This is similar in function to the means above described whereby the release of both the end relays z and I^e opens the circuits through which the slow-release relays 34 are able to reenergize relays 40 and I , that is to say, both strings of relays.

Relay za by its grounded right-hand armature and contact holds energized the solenoid 53 over the circuit including conductor 52, the winding of 53, solenoid locking spring 54, conductor 55, to grounded battery.

The solenoid 53, while energized, maintains the valve rod 56 and valve 57 in the upward position shown. 58 is the body of an electro-pneumatic valve which comprises solenoid 53, valve rod 56 and valve 57, and is shown in section. 59 is an air pressure connection from the brake-controlling air-line of the train. It is assumed that a reduced pressure in this air-line applies the brakes. 61 is a tension spring to assist gravity in opening the valve 57 when solenoid 53 is deenergized. 62 is a manually operable key for closing the circuit of the solenoid when it is deenergized and when in consequence spring 54 is not in contact with conductor 55. Numeral 63 indicates

an insulated mechanical connection to a pressure gauge or the like (not shown), connected to the air-brake system in such a way that if brakes are applied adequately, 63 presses against a contact spring 64, closing a circuit from ground through conductor 65, through the left-hand coil of relay y to battery. Thus 64 is an alternative to and in multiple with the right-hand armature of relay z . Spring 64 also closes a circuit through conductor 65^a and the left-hand winding of relay I^e to grounded battery. Thus, in relation to relay I^e , 64 is an alternative to and in multiple with the right-hand armature of relay I^e . 66 is a sealed receptacle or box enclosing the electropneumatic valve, the solenoid 53, the key 62 and preferably, also, enclosing the pressure gauge contact elements 63, 64. This receptacle or box and its seal may be of any well-known construction. Its purpose is to prevent the engineer from closing the electropneumatic valve, if it once opens, without leaving proof that it has been open.

Assuming the locomotive 4 to be receiving the "clear" code of Fig. 4 or any equivalent code comprising continuous, sufficiently rapid, alternations of positive and negative impulses in the track, the operation is as follows: The current flow in the track, whether gradually increasing as diagrammed in the upper line of Fig. 2, or steady as in the upper line of Fig. 3, sets up flux about the rails, a portion of which, 8, is led by the iron cores 5 of the inductors through the windings 7. The abrupt interruption, or interruption and reversal, of the current flow in the track causes the sudden dying out or dying out and reversal of the flux 8. This sets up in windings 7 a relatively high electro-motive force, the relative instantaneous polarity of which is dependent upon the original direction of current flow in the track. The electro-motive force raises or lowers the potential of the grid of the three-electrode electron tube 12 and causes a corresponding sudden increase or decrease in the plate current flow from battery 13 through filament and plate of 12, conductor 14, primary winding 16, and conductor 15. It will be noted that, as is well understood by those skilled in the art of amplification by electron tubes, this current will vary in magnitude but not in direction. By the use of the transformer elements 16, 17 and 18, these sudden increases and decreases of the plate current are again converted into positive and negative impulses in the circuit 18, 19, 21, 22, 20.

As explained above, these positive and negative impulses through the windings 21 and 22 of the polarized relay 23 throw the contact tongue 29 from side to side, alternately energizing relays 34. Relays 34 are designed to maintain their armatures attracted for a brief period after the circuit of their windings is open and this period must be some-

what greater than the period A between alternate impulses of the code of Fig. 4 or any equivalent "clear" code that may be used. Relays 34 are also designed to attract their 5 armatures 36 in a period somewhat less than the period A. Thus when the code of Fig. 4 or an equivalent is being produced in track 1, and when in consequence tongue 29 of polarized relays 23 is alternately in contact 10 with conductors 31 and 32 for equal periods of duration A, both relays 34 maintain their armatures 36 attracted and a circuit is closed from ground through these armatures, through conductor 41 and green lamp 42, to 15 battery, and in parallel with the latter, through conductor 67, left-hand armatures of relay z and I^c, conductor 39, and left-hand windings of relays 40 and I, to battery. The green signal light burns steadily and relays 20 40 and I remain energized. Relay 40 by its left-hand armature maintains relay 50 energized. Relay I by its left-hand armature maintains relay II energized. Relay 50 by its right-hand armature maintains relay 60 en- 25 ergized and so to the end of the "caution" series, all the relays 40 to z remaining energized. Relay II maintains relay III energized and so to the end of the "occupied" series, all the relays I to I^c remaining energized. One of the right-hand armatures of 30 relay z closes the circuit of the yellow signal lamp 51, which burns steadily. Relay z, by its right-hand armature, and relay I^c by its right-hand armature, maintain closed the circuits, including conductor 68, of the left-hand winding of relay 40^a. Relay 40^a holds 35 energized the next relay and so on to relay za, which, by its grounded right-hand armature and through conductor 52, maintains solenoid 53 energized through spring 54 and 40 conductor 55 to battery. Solenoid 53 holds closed the valve 57 and air from the brakes cannot escape from valve chamber 58. Relays z and I^a both, by their right-hand armatures, keep red lamp 51^a lighted.

The only moving elements in the circuit on the locomotive under these conditions are the armature and tongue 28 and 29 of polarized relay 23, the continuously revolving interrupters 45 and 45^a connected to a locomotive wheel, and the timer T. This may be called the normal or locked condition of the receiver.

Assuming now the locomotive to be on track containing the "caution" or speed limiting code of one of the types illustrated in Figs. 5-8 or equivalent, the operation is as follows:

Omitting the repetition of the detailed operation of receiving, amplifying and trans- 60 forming the impulses, it will be clear from the preceding explanation that at the beginning of one of the "caution" code intervals, or code pauses designated by the letter B in Figs. 5-8, polarized relay tongue 29 will 65 be positively thrown to one side or the other

and will there remain until the end of the period B. The period B is much longer than the period during which relays 34 can, without current in their windings, maintain their armatures attracted. One of these relays 34 70 will, therefore, after the lapse of a time somewhat greater than A, release its armature and open the circuit both of the green lamp 42 and of the left-hand windings of relays 40 and I. The green lamp will go out. Relay 40 will be maintained energized by its right-hand winding for a period varying from zero to nearly the time of a complete revolution of interrupter 45, but clearly will be deenergized when wiper 44 goes over the 75 insulating segment of 45. Relay 40 will then unlock itself by its right-hand armature so that it cannot be again reenergized by the circuit from the ground through wiper 44 and conductor 43. The left-hand armature 80 of relay 40 being released, deenergizes the right-hand winding of relay 50, which remains energized by its left-hand winding until wiper 46, in its turn goes over the insulating segment of 45. Relay 50 is then un- 85 locked and deenergizes one winding of 60 which is next unlocked by interrupter 45, one-half revolution later, and so on. Similarly, relay I will be maintained energized by its right-hand winding for a period varying from zero to nearly the time of a third of a revolution of interrupter 45^a, but will be released when wiper 44^a goes over the first 90 insulating segment of 45^a. Relay I will then unlock itself by its right-hand armature so that it cannot be reenergized by the circuit from ground through interrupter 45^a and wiper 44^a. The release of relay I deenergizes the right-hand winding of relay II, 95 which remains energized by its left-hand winding until wiper 46^a, in its turn, comes onto an insulating segment of 45^a. Relay II is then unlocked and deenergizes one winding of III, which is next unlocked by interrupter 45^a one-sixth of a revolution later, 100 and so on.

The relays of the two series are thus unlocked one after the other at intervals measured by a half revolution of interrupter 45, and a sixth of a revolution of interrupter 45^a, respectively. The rate at which the two series of relays are unlocked is therefore directly dependent upon the speed of the train.

Recalling that we are discussing operation in a "caution" block and that the speed in such a block is to be limited by the string of relays 40 . . . z, it becomes clear that excessive speeds, speeds such that relay z can be deenergized in the caution code time interval B, should also in all cases deenergize relays 115 I . . . I^c in the same time or less. Otherwise relay I^c, if energized, would hold up the "time of grace" string 40^a . . . Z^a. This result is obtained by so choosing the number 120 of the relays I . . . I^c and the number of the 125 130

interrupting segments in 45^a that, at any given speed, the time of counting down the string I . . . I^c is less than half the time of counting down the string 40 . . . z. That this accomplishes the result will be evident from the following facts and reasoning:

At the limit of speed permitted in an "occupied" block, i. e., at a speed very considerably less than the maximum speed permitted in a "caution" block, the time of counting down the relays I . . . I^c is just barely greater than the time between pulses of timer T. This latter time is a constant. The action of timer T is discussed below. From this fact it follows that at the speed assumed, excessive for a "caution" block, the time between pulses of timer T will be materially greater than the time to count down the relays I . . . I^c. Since this counting down time is less than half the counting down time of 40 . . . z, it does not matter where a pulse from timer T occurs, if any. For if one does not occur within the first half of the counting down time of relays 40 . . . z, then relay I^c will be released, severing the connection between conductors 80^a and 79^a and rendering the timer pulse ineffective to reenergize I . . . I^c when it does occur. On the other hand, if the timer pulse occurs at some instant within the first half of the counting down time of relays 40 . . . z, restoring all the relays I . . . I^c, then there will remain time enough thereafter fully to count down again the relays I . . . I^c. Moreover, the next pulse of timer T will not occur before this is accomplished, because at the speed assumed (a speed excessive for a "caution" block), the time between pulses of T is greater than the counting down time of I . . . I^c.

We may therefore in discussing excessive speeds in "caution" blocks, depend upon relay I^c being deenergized before relay z, and may therefore discuss the operation as though only the string of relays 40 . . . z were involved.

If, then, the speed of the train is higher than the limiting speed predetermined by the "caution" code in use, and if we assume that the engineer is negligent and has not noted the "caution" signal on the roadside semaphore, if there is one, and has likewise not seen the extinction of the green signal light in the cab of the locomotive and acted promptly, then relay z, which is the second from the last relay of the first series, will release its right-hand armature, extinguishing the yellow signal light 51 and the red signal light 51^a. This red light is multiply controlled, by the right-hand armatures of relays z and I^a, but, as just proven, relay I^a will at this time have been released. Relay y and relay z are next unlocked. Relay z, by its extreme left-hand armature, opens the connection between conductors 67 and 39. This

connection, as just shown, is already open at the left-hand contact of relay I^c.

This effectually prevents the next track impulse, at the end of the "caution" code interval B, from reenergizing the relays 40 . . . z. In other words, if relay z is deenergized under the conditions of excessive speed in a "caution" block, a brake application becomes unavoidable.

If the engineer did not apply the brakes when the green lamp went out, he should do so at once when the yellow and red lamps go out. Should he fail to do this also, then the string of relays 40^a . . . Z^a, that I term "time of grace" relays, will be released one after the other, and when the last relay Z^a is released, the solenoid 53 is deenergized, opening the electropneumatic valve 57, reducing the air line pressure and applying the brakes. However, if the engineer at any instant before the "time of grace" is exhausted, i. e., before relay Z^a is deenergized, has made an effective brake application so that the air line pressure is reduced sufficiently to cause member 63 to press contact 64 against conductors 65 and 65^a, there is a circuit established from ground through each of these conductors and the left windings of relays y and I^b. These relays are thus energized and energize, respectively, by their left-hand armatures, the relays z and I^c, thus closing the restoring circuit from conductor 67, through the left-hand armatures of z and I^c, through conductor 39 and the left-hand windings of relays 40 and I to battery and ground. This reestablishes the condition in which a new track impulse, by the energization of the deenergized slow-release quick-acting relay 34, is able to restore relays 40 and I and hence to restore both strings of relays 40 . . . z and I . . . I^c.

If now, being in a "caution" block, the engineer keeps on his brakes until his speed is within allowed limits, the interrupter 45 will not release the relays 40 . . . z before each new track impulse restores them. He should, in fact, keep on the brakes until relay z is never released. It will be noted that while the speed is being brought down to the required limit for a "caution" block, relays 34 are operating and releasing alternately causing the successive operation and release of the chain 40 . . . 40^a. The yellow and red lamps therefore flicker each time this string of relays is counted down. When the allowable speed is reached relay z remains operated. The yellow and red lamps will then burn steadily, and he may then take off his brakes. At this time, and at all times in a "caution" block, his green light will flash up once every caution cycle, i. e., at time interval B.

If the engineer failed to make a manual application of brakes before his "time of grace" relays were all released, and if therefore relay Z^a releases solenoid 53 and causes an automatic brake application, the same circuits

are closed that are closed by a manual application, namely, from ground through contact 64, conductors 65 and 65^a, and the left-hand coils of relays y and I^b , to grounded battery, and the restoring circuit is made ready whereby a track impulse when it occurs sets up both strings of relays. But the engineer after an automatic application cannot release the brakes without closing the electropneumatic valve which is now open. And to do this he must open the box or enclosure 66, breaking the seal thereof, and incurring a demerit upon his arrival at an inspection point. Key 62 is provided within box 66 to restore sole-
15 noid 53.

Thus, to summarize, after an automatic brake application the engineer cannot release the brakes without unsealing the box. But by a manual application of the brakes, i. e., if 20 just before relay Z^a and solenoid 53 are de-energized, the circuits from ground through 64, through 65 and 65^a and the right-hand windings of relays y and I^b to battery and ground are closed, the deenergization of the 25 solenoid will be forestalled and he will not have to open the box.

Instead of pneumatic pressure or other pneumatic means to close the contacts 64, 65 and 65^a when the brakes are applied, any well-known or obvious mechanical, electrical or other means may be employed. This is a matter in which the nature of the braking system in use will be controlling, and one that will offer no difficulties to those skilled in 35 the art. As stated above, contacts 64, and the connecting wires 65 and 65^a are preferably located in sealed box 66. It may be more convenient to locate them elsewhere. They should be so devised as not to be operable 40 except by a brake application of predetermined force or greater, and not to be accessible for tampering.

It will be noted that a small margin of 45 safety as to speed is provided by connecting lamps 51 and 51^a to relays one or two earlier in the two series than the end relays z and I^c . If, without this margin of safety the engineer should unconsciously allow the train to speed up a very little, he might receive an automatic 50 application of the brakes which would not be heralded by brief extinctions or flickerings of red and yellow lamps 51 and 51^a.

It will be noted that the cab signal lamps 55 42, 51 and 51^a are not affected by the restoring of relays y and I^b by any brake application. The relay 40 . . . z are still subject to their two conflicting controls, the polarized relay by way of relays 34; 34 tending at intervals to 60 restore them and the interrupter 45 tending steadily to deenergize them one by one. Thus the lamps continue to give significant indications as to the code that is being received, particularly lamp 42, and as to whether the train 65 speed has or has not been brought within the

required limit, particularly lamps 51 and 51^a.

In view of the foregoing explanations the action of any "occupied" code will be immediately clear. One of the relays 34 releases 70 its armature permanently or until the "occupied" code is succeeded by "caution" or "clear" code. The green lamp goes out permanently. The relays 40 . . . z and I . . . I^c are counted down. Relays 40 . . . z are not re- 75 stored by the polarized relay, since no effective track impulses are coming in, nor I . . . I^c by timer T , which is disconnected at I^c . The red and yellow lamps next go out per- 80 manently.

As before, and for the same reasons, the engineer must at once apply his brakes or they will be applied for him. If he applies them in time (i. e., before relay Z^a is released), he will avoid an automatic application. Since 85 we are in an "occupied" block, i. e., one in which no track impulses will occur to restore the deenergized one of slow-acting relays 34, the string 40 . . . z will be very quickly re- 90 leased through to the end relay z , and will not be restored. Yellow lamp 51 will go out and will not be relighted. Green light 42 has already gone out.

If, as we assume first, the speed of the locomotive is beyond the low speed (say 15 miles 95 per hour) permitted in an occupied block, then the string of relays I . . . I^c will also very quickly be deenergized entirely. Without repeating the reasoning given hereinbefore, it can be stated that relay I^c will be released be- 100 fore relay z . Thus red light 51^a will go out simultaneously with 51.

The instant green light 42 went out the engineer should have applied the brakes. If he thought the block being entered was a 105 "caution" rather than an "occupied" block and thought his speed proper for a "caution" block and thus delayed his action, he is further warned by the extinction of the red and yellow lights, and is thereafter, as before, 110 bound to make a manual brake application in the "time of grace", i. e., before relays 40^a . . . Z^a are all deenergized. If he does not, an automatic application is made, the seal of 115 66 has to be broken, and he is presumably disciplined.

Let us assume that at some instant after green light 42 went out and before Z^a fell, he did make a manual application of the brakes. Just as described in "caution" block operation 120 relays y and I^b are reenergized, which does not affect the above description of the functioning of the green or yellow lamp, but does permit timer T to restore periodically the string of relays I . . . I^c by the circuit from 125 ground through wiper t , conductor 80^a, right-hand contact of relay I^c , conductor 79^a, right-hand winding of relay I to grounded battery. This establishes a condition in which interrupter 45^a counts down one by one (six to a 130

revolution, as shown) the relays $I \dots I^c$ and in which timer T restores them all at intervals. While the brakes are reducing the speed to within the permissible limit the interrupter 5 will be able to get all the relays counted down before the timer T restores them. Thus red lamp 51^a will go out, briefly, it may be, and light up again. When the speed is sufficiently reduced, the interrupter will each time fail to 10 reach relay I^a before the timer restores the string, and red lamp 51^a will burn steadily. When this signal is observed, i. e., green and yellow lamps both out and red lamp burning, the engineer knows he is in an "occupied" 15 (or a "stop") block but running within prescribed speed limits, and he may take off the brakes, and keep them off provided he does not speed up too much. If he accelerates a little too much, the red light will be extinguished very briefly repeatedly. If he accelerates still more it will go out and stay out. Both are warnings to apply the brakes again 20 at once under the usual penalty of an automatic application.

25 It will be clear from the above what will be the conditions when the engineer enters an "occupied" block at a speed within the allowed limit. The green and yellow lights will go out and the red light will burn. The 30 relay string $40 \dots z$ will be counted down and remain deenergized and the string $I \dots I^a$ will be repeatedly counted down to some point short of I^a and set up again by timer T. Relay I^c will hold the "time of grace" relays 35 $40^a \dots Z$ and hence the solenoid 53 all energized.

When the code changes either to "caution" (slow track impulses) or to "clear" (quick track impulses), the circuit through 67 and 40 39 whereby the relays 34 reenergize relays 40 $\dots z$ will be found available, being held closed at the left-hand armature of relay I^c . Thus the proper lamp response will be made to a change of code indication in the track.

45 If such change is to "caution," the green light lights up for a second every code interval, B. The relays $40 \dots z$ are all energized at the same intervals, also $I \dots I^c$; the interrupters 45 and 45^a deenergize, respectively, 50 these two strings of relays as far down as they have time between track impulses. And the yellow lamp burns, unless of course, the speed is still above that permitted in a "caution" block. The red light also burns unless 55 the speed is excessive. The operation is now, therefore, exactly as described above under "caution" block operation.

If such code change is from "occupied" to "clear", the two slow-release quick-acting 60 relays 34 will both become and stay energized. This lights the green lamp steadily. The relays $40 \dots z$ and $I \dots I^c$ will all be energized. Yellow and red lights burn. Everything is again as described above under 65 "clear" block operation.

In Fig. 11, S is a source of electrical energy, (see Fig. 1), and is here shown as a battery associated with a protective resistance and a fuse F. The source S might equally well be a generator or power lines fed from a distant source. To cooperate with the structure of the track current code controller 6 shown, S must be a source of direct current. My invention, however, may be variously practiced, as was suggested above, and among 75 other variations S may be a transformer or set of transformers or of power lines selectively delivering (conductively or inductively) into the track circuit series of current waves of substantially the characteristics 80 shown in Fig. 2 and of the proper sequence, polarity and timing to constitute the required code for the conditions of the moment. In other words, the code currents may be produced at a distance, instead of locally, by 85 a battery and interrupters as shown and as I am about to describe in detail, transmitted over wires to the different controllers 6 along the roadbed, and selectively fed by them to the track circuits in substantially the same 90 manner as, in Fig. 11, I feed the locally generated codes.

In controller 6, shown in Fig. 11 surrounded by a dotted line, 69 is an interrupter or rather a reverser or pole-changer fed by the 95 battery leads 71, 72, respectively, + and -, through wipers 73 and 74 bearing on collector rings 77 and 78. Wipers 75 and 76 bear alternately on the + and the - conducting segments of reverser ring 79. The insulation between these segments is wider than the bearing surface of 75 and 76 so that they are both simultaneously insulated from the source S for a very brief instant. Wipers 75 and 76 and the leads 81 and 82 therefrom, thus deliver for a brief period a supply of steady 105 current alternating in polarity rather than ordinary or sine wave alternating current. The frequency of the alternations is determined by the speed of shaft 83 which I have marked "fast" in the drawing. Reverser 69 produces "clear" codes.

Shaft 83 may be driven by any suitable motor, e. g., an electric motor drawing energy 115 from source S, and this motor must have quite constant speed. A small D. C. motor with governing means to compensate for voltage changes would be suitable. Shaft 83, being properly geared to the motor, revolves at such a speed that one half-revolution takes the time A of the "clear" code.

84 is an exactly similar reverser, except that the speed is such as to produce the "caution" code. It need not be further described. Conductors 85 and 86 then deliver slow 125 reversed direct current according to the code of Fig. 5 and with wave forms substantially like those of the upper line of Fig. 3. The shaft of reverser 84 is preferably geared, in 130

proper speed relation to shaft 83, to the same motor.

The wave forms of Fig. 3 show no break or bend in the curve between the interruption of, let us say, a positive current flow and the establishment of negative flow. This is possible, by reversers like 60, if the time during which wipers 75 and 76 are entirely insulated from the battery is more brief than the time necessary for the current flowing in the track circuit to decay to zero. This requires, if accidental short circuits are to be avoided, either a very close adjustment of the widths of the insulation and of the wipers, or a relatively large surface speed of reverser ring 79. The latter is preferable and obtainable by making the diameter of 79 large in relation to the width of wipers 75 and 76.

It is noteworthy, however, that using as I do in Fig. 10 an unbiased polarized relay, this refinement is not necessary. If, some time after current in the one direction has been interrupted, current in the opposite direction is sharply set up in the track, the result so far as the receiving circuit on the locomotive is concerned is merely that two impulses of the same polarity are received in rapid succession. The first will have practically always the higher voltage and the shorter duration and will operate the polarized relay. The second will have no effect.

Moreover, other forms of reversing devices, with a quick spring or magnetic action, are well known and can be equally well used. The commutator and carbon brush type I find preferable from the standpoint of general durability and reliability of contact. In any case, should either reverser slow up, stick, break contact, or be short-circuited and below the fuse F, the code fed to the track will enforce a lower train speed, or produce the effect of "stop" code.

87 is a biased polarized relay, and it is shown biased by a spring 88, though it may be biased by unbalanced polarizing flux, and, for the simplicity of the drawing only, it is shown with a permanent polarizing magnet 89 instead of a polarizing winding. Its armature is grounded. It is connected across the entering end of block or section of track No. 1. It constitutes, together with conductors 91, 92 the circuit connection 3 of Fig. 1 which completes the track circuit for this block. The track circuit in each block is normally closed through the windings of relay 87, but when a train enters the block, the track circuit is closed through the wheels and axles thereof.

In Fig. 11, though the rear or entering ends of two blocks Nos. 1 and 2 are visible, the drawing of relay 87 has not been repeated for block No. 2, and conductors 91^a, 92^a leading to another and, to be imagined, similar polarized relay across block No. 2, are merely indicated ending in arrows. This is also the treatment of the two visible front or exit ends

of blocks Nos. 2 and 3, and of the conductors 93, 94 or 93^a, 94^a feeding them from code controllers 6. Only controller 6 feeding block No. 2 is shown.

Tongue 95 of relay 87 alternately makes contact, either rapidly or slowly, with conductors 96 and 97, if in block No. 1 the existing code is "clear" or "caution." Two extra slow relays 98 are thus energized by tongue 95, one through conductor 96 and one through conductor 97. Relays 98 are shown equipped with heavy copper collars to indicate slowness. They are preferably of a mechanically retarded type, because of the expense of making an electrically retarded relay as slow as these are required to be, if the "caution" interval B is taken of the order of seven seconds as suggested above. The preferred retardation, if such long code intervals are chosen, is of a well-known type involving angular acceleration of a balanced mass or flywheel by a relatively weak force applied by the attracted armature, and is such that the energy of successive impulses is largely stored in the mass. A weak spring or light weight opposes the armature attraction. If, however, more rapid "caution" codes are chosen, electrically sluggish relays are suitable, and can be produced at reasonable expense.

When, therefore, either "clear" or "caution" code is in block No. 1, extra slow relays 98 attract and hold attracted their armatures and a circuit is closed from battery through their armatures in series, through conductor 99 and the winding of relay 101, to ground. Relay 101 attracts its two armatures and connects the leads 81, 82 which yield "clear" code, to the track feed wires 93 and 94 of block No. 2. Thus "clear" or "caution" in one block establishes "clear" in the block behind.

Let us assume that in block No. 1 the "stop" code is set up. As the polarized relay 87 is, more or less fortuitously, shown biased to respond to positive current, it is necessary to choose as the "stop" code to cooperate therewith the one shown on the third line of Fig. 9, i. e., continued steady current in the positive direction. Oppositely biasing the relay 87 would require using for "stop" code a continued negative current. Assuming then a continued positive flow in block No. 1 and therefore through conductors 91, 92 and the winding of relay 87, the right-hand extra slow relay 98 is held energized, but the left-hand relay releases its armature. It is readily seen that a circuit is thus closed, energizing relay 102 and thereby applying to feed wires 94 and 95 the "caution" code always in leads 85 and 86. Relays 101, 102 and 103 must be relatively quick to release and slow to operate in order that two codes shall not be fed simultaneously with resultant probable short circuits. We now have "stop" code in block No. 1, causing "caution" code to be fed

to block No. 2. This, in turn, will cause "clear" code to be fed in block No. 3.

Assume now that block No. 1 is occupied and that the entering end is therefore currentless. Relay 87 lies as shown in Fig. 11. Relays 98 stay as shown and a circuit is set up energizing relay 103 and feeding steady current in the positive direction from battery leads 71, 72 to feed wires 93, 94 and to the track of block No. 2. This is the "stop" code chosen. We thus have the occupied block No. 1 setting up "stop" code in block No. 2. This in turn, as detailed above, sets up "caution" code in block No. 3, which again sets up "clear" code in block No. 4. And "clear" code in block No. 4 reproduces itself in block No. 5, and so on.

What I claim is:

1. In a train control system, a vehicle, a timing device on said vehicle constantly operating independently of track conditions, a set of counting relays on said vehicle, means for operating said relays in one sense under the control of a wheel of said vehicle, and means controlled by said device for operating said relays in the opposite sense.

2. In a train control system, a vehicle, a set of counting relays on said vehicle, means controlled by a wheel of said vehicle for successively deenergizing said counting relays, and a uniformly operating timing device on said vehicle for successively energizing said relays independently of track conditions.

3. In a train control system, a vehicle, an interrupter operated by said vehicle, a set of counting relays on said vehicle, circuits controlled by said interrupter for successively deenergizing said relays, a timing device on said vehicle uniformly operating independently of track conditions, and circuits controlled by said timing device for successively energizing said counting relays.

4. In a train control system, a vehicle, an interrupter operated by a wheel of said vehicle, a set of counting relays on said vehicle, an energizing circuit for the first counting relay, energizing circuits successively closed for the other counting relays upon the energization of said first relay, locking circuits for said relays controlled by said interrupter, and an interrupter on said vehicle constantly operating independently of track conditions for controlling the energizing circuit of said first counting relay.

5. In a train control system, a track section, a vehicle movable thereon, an interrupter operated by a wheel of said vehicle, a set of counting relays on said vehicle, means for producing in said track section codes of electrical impulses corresponding to different operating conditions for said track section, an energizing circuit for the first counting relay closed in response to a certain code, energizing circuits successively closed for the other counting relays upon the energization

of the first relay, a locking circuit for each one of said counting relays controlled by said interrupter, a visual signal actuated upon the deenergization of a certain one of said counting relays, and an interrupter on said vehicle constantly operating independently of track conditions controlling the energizing circuit of the first counting relay.

6. In a train control system, a track, a vehicle, means to produce track indications, means on said vehicle controlled by the track indications to limit the speed of said vehicle to one limit, a device on said vehicle marking off uniform intervals of time, a device on said vehicle marking off uniform distances of vehicle travel, and means cooperatively controlled by said last two means to limit the speed of said vehicle to another and lower limit.

7. In a train control system, a track, a vehicle, means partly on the ground including said track and partly on said vehicle to exert vehicle speed-limiting control under one set of conditions, and means wholly on said vehicle to exert vehicle speed-limiting control under another set of conditions, said last mentioned means comprising a timing device constantly operating independently of track conditions and including means for continuously comparing the timing of said device with the speed of the train and for comparing the timing of said device with the track conditions.

8. In a train control system, a track, a vehicle, means partly on said vehicle to give speed-limiting indications when said vehicle exceeds a limiting speed for one set of conditions, and means wholly on said vehicle to give speed-limiting indications when said vehicle exceeds a lower limiting speed for another set of conditions, said last mentioned means comprising a timing device constantly operating independently of track conditions and including means for continuously comparing the timing of said device with the speed of the train and for comparing the timing of said device with the track conditions.

9. In a train control system, a track, a vehicle, means partly on the ground including said track and partly on said vehicle to give speed-limiting control when said vehicle exceeds a permissible limiting speed for one set of conditions, and means wholly on said vehicle to give speed-limiting control when said vehicle exceeds a lower permissible limiting speed for another set of conditions, said last mentioned means comprising a timing device constantly operating independently of track conditions and including means for continuously comparing the timing of said device with the speed of the train and for comparing the timing of said device with the track conditions.

10. In a train control system, a track, a

vehicle, brakes on said vehicle, means including said track to apply said brakes when said vehicle exceeds a permissible limiting speed for one set of conditions, and means wholly on said vehicle to apply said brakes when 5 said vehicle exceeds a lower permissible limiting speed for another set of conditions, said latter means comprising an impulsor of frequency proportional to the speed of said vehicle, an impulsor of uniform independent frequency and an electromagnetic register including a series of relays oppositely operated by said two impulsors and an electromagnetic brake control means controlled by 10 said register.

15 11. In a train control system, a track, a vehicle, brakes on said vehicle and at least one speed-limiting device wholly on said vehicle comprising a chronometer, an odometer, a comparator means oppositely controlled 20 by the two and determining the operation of said brakes when predominantly controlled by said odometer, and a brake operating means including another odometer to delay 25 operation of said brakes for a definite distance of vehicle travel after said comparator means has determined the operation of said brakes.

12. In a train control system, a track, a vehicle, brakes on said vehicle, at least one 30 speed-limiting device wholly on said vehicle comprising a circuit closer of a constant speed, an interrupter of a speed dependent upon the vehicle speed, a comparator means comprising an electromagnetic counter registering 35 revolutions of said interrupter and returned to normal at constant time intervals by said circuit closer, and a brake-applying means to apply said brakes when the counter of said comparator means registers a predetermined 40 number of revolutions of said interrupter before it is returned to normal by said circuit closer.

13. In a train control system a track, means 45 for impressing on said track currents of different characteristics each corresponding to a maximum allowable speed for said vehicle, a register device jointly controlled in accordance with said currents and in accordance with the vehicle speed, a second register device 50 jointly controlled in accordance with said currents and in accordance with a device having a constant speed, each of said registers corresponding to a different range of vehicle speed and effective to control the 55 automatic braking of said vehicle when the corresponding speed range is exceeded.

14. In a train control system a vehicle, a registering device on said vehicle to be operated in accordance with track currents and 60 released in accordance with the speed of said vehicle, a second register device also operated in accordance with track currents and released in accordance with the speed of said vehicle, means for effecting the release of said second 65 register at a different rate from the release

of said first register, and means for comparing the release of said second register with a constant speed device.

15. In a train control system, a trackway, means for applying to said trackway currents corresponding to different operating conditions in said trackway, a vehicle, a first set of counting relays on said vehicle, means for controlling said counting relays by the track currents, means controlled by a wheel of said vehicle for simultaneously controlling said first set of counting relays, a second set of counting relays adapted to be controlled by the track currents, other means controlled by a wheel of said vehicle for simultaneously controlling said second set of counting relays, and a uniformly operating timing device on said vehicle for controlling the second set of counting relays.

16. In a train control system, a trackway, means for impressing on said trackway electrical impulses corresponding to different operating conditions in the trackway, a vehicle, a first set of counting relays on said vehicle adapted to be selectively energized by the track currents, a second set of counting relays on said relays also adapted to be selectively energized by the track currents, means for comparing the energization of each of said sets of relays with the speed of the train, and a uniformly operating timing device for controlling the energization of one of said sets of counting relays.

17. In a train control system, a trackway, means for impressing on said trackway electrical impulses corresponding to different operating conditions in the trackway, a first step-by-step device adapted to be operated under control of the track currents for one set of track conditions, and a second step-by-step device adapted to be also controlled by the track currents for another set of track conditions, an automatic braking means for said vehicle adapted to be operated when either of said step-by-step devices has been operated to a predetermined extent, and a uniformly operating timing device on said vehicle for controlling the extent of operation of one of said step-by-step devices.

18. In combination on a railway train, a series of relays, means for causing successive release of said relays at a rate proportional to the speed of the train, a brake application valve set into operation when the last relay of said series releases, and means for preventing said valve from being set into operation upon release of said last relay if the train speed has been reduced.

In testimony whereof, I have signed my name to this specification, this 19th day of April, 1926.

ARTHUR H. ADAMS.
